Balloons and Weights Turquoise Blue E-Z Balloon Cup and E-Z Balloon Stick by Walmart, dated 2018, found online [Jun. 18, 2018] https://www.walmart.com/ip/Balloons-and-Weights-Turquoise-Blue-E-Z-Balloon-Cup-and-E-Z-Balloon-Stick-Holders-250-Piece/40268272.*

Primary Examiner — Brandon M Rosati*Assistant Examiner* — Marissa J Cash(74) *Attorney, Agent, or Firm* — Fay Sharpe LLP(57) **CLAIM**

The ornamental design for a combined balloon cup and stick, as shown and described.

DESCRIPTION

FIG. 1 is a side plan view of a combined balloon cup and stick of the present application;

FIG. 2 is a side perspective view thereof;

FIG. 3 is a second side plan view thereof;

FIG. 4 is a top plan view thereof;

FIG. 5 is a side plan view thereof;

FIG. 6 is a back plan view thereof; and,

FIG. 7 is a bottom plan view thereof.

The broken lines shown in FIG. 1 form no part of the claimed combined balloon cup and stick and are included for the purpose of illustrating environment only; The combined balloon cup and stick is shown with a symbolic break in its length. The appearance of any portion of the article between the break lines forms no part of the claimed design.

1 Claim, 4 Drawing Sheets(56)
